(**) Term: **14 Years**

(57) **CLAIM**

(21) Appl. No.: **29/472,735**

The ornamental design for a digital camera, as shown and described.

(22) Filed: **Nov. 15, 2013**

DESCRIPTION

(30) **Foreign Application Priority Data**

May 16, 2013 (KR) 30-2013-0025774

(51) **LOC (10) Cl.** **16-05**

FIG. 1 is a rear perspective view of a digital camera showing

(52) **U.S. Cl.**

my new design;

USPC **D16/219**

FIG. 2 is a front view thereof;

(58) **Field of Classification Search**

FIG. 3 is a rear view thereof;

CPC G03B 15/03; G03B 17/02; G03B 17/04;

FIG. 4 is a left-side view thereof;

G03B 17/56; G03B 19/04; H04N 5/2251;

FIG. 5 is a right-side view thereof;

H04N 5/2252; H04N 5/2253; H04N 5/2254;

FIG. 6 is a top view thereof;

H04N 2101/00

FIG. 7 is a bottom view thereof;

USPC D16/200, 202–206, 208, 218, 219, 242;

FIG. 8 is an enlarged view of the encircled portion as shown

348/373–376; 396/535, 539–541

in FIG. 1;

See application file for complete search history.

FIG. 9 is an enlarged view of the encircled portion located at

(56) **References Cited**

the top right side of FIG. 2;

U.S. PATENT DOCUMENTS

FIG. 10 is an enlarged view of the encircled portion located at

D502,199 S * 2/2005 Imai D16/202

the bottom center of FIG. 2; and,

D503,417 S * 3/2005 Kawase D16/202

FIG. 11 is an enlarged view of the encircled portion as shown

D506,767 S * 6/2005 Imai D16/202

in FIG. 3.

D548,257 S * 8/2007 Onuma et al. D16/202

The broken lines depict portions of a digital camera in which

D567,835 S * 4/2008 Sumita D16/202

the design is embodied and form no part of the claimed

D581,440 S * 11/2008 Nakamura D16/202

design.

D594,892 S * 6/2009 Kamiya et al. D16/202

The dot-dash broken lines encircling portions of the claimed

D611,976 S * 3/2010 Kim et al. D16/202

design that are illustrated in enlargements form no part of the

claimed design.
